UNITED STATES PATENT OFFICE.

JOHN E. WINDLE, OF WORCESTER, MASSACHUSETTS.

CLOTH-WINDING MACHINE.

SPECIFICATION forming part of Letters Patent No. 608,817, dated August 9, 1898.

Application filed July 26, 1897. Serial No. 645,909. (No model.)

To all whom it may concern:

Be it known that I, JOHN E. WINDLE, of Worcester, county of Worcester, and State of Massachusetts, have invented an Improvement in Cloth-Winding Machines, of which the following description, in connection with the accompanying drawings, is a specification, like letters on the drawings representing like parts.

10 In machines for winding cloth upon a board or other receiver for measuring it is necessary to turn the board or receiver automatically while the cloth is being wound tightly upon it, and at such times said board must be held firmly, and when the board has been filled it is very desirable to very quickly remove the filled board from the machine. The board or receiver upon which the cloth is wound is usually clasped between forked 15 or other shaped ends of two rotatable journals, and when the board was to be rotated it has been customary to rotate a screw which pressed against the outer end of the journal, thus forcing its inner end firmly against the board, and to remove a filled board this screw 20 has had to be reversed in its movements and its end moved away from the outer end of the journal, this requiring a very considerable loss of time. I have devised means whereby 25 one of these journals for rotating the board may be quickly moved into position to engage the board and may be moved quickly out of position in the reverse direction to enable the journal to be quickly detached from 30 the board when it is desired to remove the latter.

In my invention I have extended the longitudinally-movable journal of the usual pair of journals into a sleeve, said sleeve being 35 provided with a follower having coöperating with it suitable actuating means to be described, said means being actuated by a partial rotation in one or the other direction of a shaft, the movement of the said shaft in 40 one direction causing the follower to force the journal against the board, while the movement of the shaft in the opposite direction enables the journal to be quickly moved away from the board. This shaft and the means 45 operated by it to impart movement to the follower is always positive, and to compensate 50 for any variations in length of the board I

have combined with the follower a spring which may yield as the latter is being actuated to force the holding end of the journal 55 against the board or other receiver. By the employment of bent links connected with cranks or disks fixed to the shaft referred to it is possible when the said shaft is turned to effect the forcing of the journal against the 60 board that the crank-pins will pass the dead-center of the shaft, thus locking the journal in operative position.

Figure 1 represents a sufficient portion of a cloth-winding machine to enable my invention to be understood. Fig. 2 is an enlarged longitudinal section of the parts herein to be claimed as of my invention. Fig. 3 is a sectional detail on the line xx of Fig. 2.

The framework A , the roller A' , mounted 70 therein, the shaft B , having like toothed pinions b' engaging, respectively, the wheels b^2 b^3 , said wheels being suitably sustained in a framework a , and the journal d' for the wheel b^2 , said journal having its inner end 75 suitably shaped to embrace or engage the board c , on which is to be wound the cloth c' , are and may be all as usual, so need not be herein further described.

The journal d , shaped in usual manner to 80 engage the opposite end of the board, is splined loosely in the hub of the toothed wheel b^3 , so that it may slide back and forth in said hub as required to effect the removal from the machine or the putting into the machine 85 of a board.

The framework a at the right in Fig. 1 has attached to it in suitable manner the ears e of a sleeve e' , said sleeve having, as represented, a slot e^2 . The outer end of the 90 journal d after passing through the said wheel b^3 enters the sleeve e' , as represented in Fig. 2, it abutting, as shown, against a leather or other washer f , connected with a follower f' , mounted loosely in said sleeve. 95

This follower has combined with it actuating means, said means being herein represented as a shaft g^2 , having fixed to it disks g' , having crank-pins m , said crank-pins each receiving one end of a suitable bent link g , 100 said link being jointed to the end of a bar f^2 , extended, as herein shown, through the slot e^2 of the said sleeve, and preferably there will be placed between the said follower and

the said bar a suitable strong spiral or other spring f^3 . The shaft g^2 may be extended through the sleeve and occupy a position within the sleeve, and in such construction the follower will be cut away at its side next to the shaft, the said shaft acting to prevent rotation of the follower.

It is desirable to have the shaft g^2 extended through the sleeve, as represented, for the reason that when the said journal is pressed against the cloth-board by the follower it will be there held against any accidental longitudinal movement by reason of the center of the crank-pins m being carried beyond the center of the shaft g^2 , the bent links g permitting such relative position of the crank-pin and shaft.

It is preferred to connect the links g to the bar f^2 ; but this invention would not be departed from if the links were connected to the opposite ends of a stud f^5 , (shown by dotted lines,) extended through the end of the follower.

Referring to Fig. 1 and assuming that the machine is in operation, the crank-pins m are between the shaft g^2 and the wheel b^3 , and in such position the end f of the follower f' is forced firmly against the outer end of the journal d , keeping the inner end of said journal firmly against and so as to hold and rotate with it the board c , on which to wind the cloth. A sufficient quantity of cloth having been wound upon the board, the operator has only to take hold of the hand-wheel h' , fast on the shaft g^2 , and turn the same for a partial rotation in the direction of the arrow near the disk g' in Fig. 2, such movement quickly releasing the follower, leaving the journal d loose or unlocked, so that it may be engaged by hand and moved quickly to the right, Fig. 1, away from the end of the cloth-board, thus quickly releasing it to be removed from the machine. When a new board has been placed with its end against the journal a' , this hand-wheel may be turned in the opposite direction by a quick movement, thus again quickly forcing the follower to the left, viewing Fig. 2, it acting on the journal d , forcing it quickly to the left, Fig. 2, against

the end of the board, thus confining it fixedly in position to be rotated.

Having fully described my invention, what I claim, and desire to secure by Letters Patent, is—

1. A cloth-winding machine, having opposite axially-alined journals separated to hold a winding-board, one of said journals being mounted free to slide longitudinally, and yielding means independent of said sliding journal for locking and unlocking it in holding position without moving it longitudinally and without interfering with its rotation, said sliding journal when unlocked being free to be slid back by hand, substantially as described. 55

2. In a machine of the class described, a cloth-board-holding rotatable and endwise-moving journal, a sleeve surrounding the said journal, a follower in said sleeve controlling the movement of the outer end of said journal, a shaft, disks fast on said shaft, crank-pins thereon, a bar, bent links connected with said crank-pins and to said bar, the partial rotation of said shaft in one direction, putting the crank-pins, to which the links are 75 connected, to one side of the center of the said shaft, to thereby lock the journal and follower in their operative position, substantially as described. 70

3. In a machine of the class described, a rotatable toothed wheel, a journal carried by said wheel and free to slide therein longitudinally, a sleeve, a follower carried by said sleeve, a shaft, and means operated thereby to move said follower and cause it to press 85 the said journal closely against the board to be held by it, said follower being partially cut away to receive said shaft and adapted to be restrained from rotation by the said shaft, substantially as described. 90

In testimony whereof I have signed my name to this specification in the presence of two subscribing witnesses.

JOHN E. WINDLE.
